ALBERT J. HORTON, OF WHITE PLAINS, NEW YORK, ASSIGNOR TO THE CUTLER-HAMMER MFG. CO., OF MILWAUKEE, WISCONSIN, A CORPORATION OF WISCONSIN.

CONTROLLER FOR ELECTRIC MOTORS.

991,206.

Specification of Letters Patent.

Patented May 2, 1911.

Application filed July 6, 1908. Serial No. 442,174.

To all whom it may concern:

Be it known that I, ALBERT J. HORTON, a citizen of the United States, residing at White Plains, in the county of Westchester and State of New York, have invented new and useful Improvements in Controllers for Electric Motors, of which the following is a full, clear, concise, and exact description, reference being had to the accompanying 10 drawing, forming a part of this specification.

My invention relates to controllers for electric motors, and more particularly to those for causing the motor to operate at 15 different speeds.

One object of my invention is to provide means whereby the motor may be operated at a slow speed for any desired period of time, and then automatically brought up to 20 any predetermined maximum speed by the manipulation of a single switch.

Other objects of my invention will be hereinafter set forth.

In the accompanying drawing I have dia- 25 grammatically illustrated one form of controller embodying my invention.

The controller shown in the drawing comprises an electromagnetically operated main switch, an electromagnetically operated 30 speed controller and a pilot switch for controlling the operation of said main switch and said controller. As will hereinafter be explained, the pilot switch also controls the direction of the flow of current through the 35 motor.

The main switch 1 is carried by the plunger 2 of a solenoid 3. This switch is provided with main contact brushes 4 and 5 and arcing contacts 6 and 7, which are carried 40 on spring arms. The brushes 4 and 5 are adapted to engage stationary contacts 8 and 9, respectively. In one position of the main switch, the arcing contacts are arranged to engage stationary arcing contacts 10 and 11, 45 and in another position of said switch to engage stationary contacts 12 and 13. The contacts 10 and 11 are connected to the contacts 8 and 9.

The speed controller, which I have shown, 50 is of the same construction as that shown in my former application, Serial No. 430,829, filed May 4, 1908. Generally described, the speed controller comprises an arm 14 pivoted at 15. At its outer end, the arm 14 carries brushes 16 and 17. As the arm 14 is

moved the brush 16 is adapted to sweep over a contact segment 18 and a series of contacts 19, while the brush 17 is adapted to sweep over a series of contacts 21 and a segment 22. The contacts 19 are connected to a field regulating resistance 20, which is also connected to one end of the segment 18. All but the first of the series of contacts 21 are connected to an armature resistance 23, which is also connected to one end of the segment 22. The 60 arm 14 is connected by an insulating link 24 to the plunger 25 of a solenoid 26. The solenoid 26 is provided with an adjustable core or plug 27 which is supported by a pivoted lever 28. The lever 28 is provided at 70 its free end with a handle 29 and a pin 30. The pin 30 is adapted to fit into any of the apertures 31 in a rack 32. This arrangement provides means whereby the lever 28 may be moved to, and maintained, in any 75 desired position to adjust the position of the plug 27 within the winding 26. The lever 28 is provided with a lug 33 to which is pivoted a switch 34. The free end of the switch 34 is adapted to engage a stationary 80 contact 35. A pin 37, extending through the plug 27 and projecting below the end thereof, provides means whereby the switch 34 will be opened by the plunger 25 when the same reaches the limit of its upward movement. By adjusting the position of the plug 27 within the winding 26, the range of 85 movement of the plunger 25 may be limited to any desired extent, which results in the limitation of the range of movement of the 90 controlling arm 14. Hence, the controller may be set to cause the arm 14 to cut out any predetermined amount of armature resistance 23 and to insert any predetermined amount of field regulating resistance 20. 95 The movement of the arm 14 is retarded by a dash-pot 38 which has its piston 39 connected to said arm. When the arm 14 is in its lowermost position, the brush 17 carried thereby, bridges the first two of the contacts 21, while the brush 16 engages segment 18.

The pilot switch comprises a movable arm 40 pivoted at 41 and provided with an operating handle 42. The member 40 is of irregular shape and carries contact brushes 43, 44 and 45 which are arranged thereon in a staggered manner and radially disposed to the axis thereof. The brushes carried by the arm 40 are elongated and are each adapted 100

105

110

- to move over and engage with two sets of contact segments, which will now be described: The upper end of the brush 43 is adapted to engage either of the contact segments 46 or 47, while the lower end of said brush engages a contact segment 50. When the arm 40 is moved to its extreme left-hand position, the brush 43 engages a contact 48, and when said arm is in its extreme right-hand position, the brush 43 engages a contact 49. At its upper end the brush 44 engages the contact segment 50, while its lower end is adapted to engage either of the contacts 51 or 52. The upper end of the brush 45 is adapted to engage either of the contact segments 52 or 53, while its lower end engages a contact segment 54. As shown in the drawing, the contact segments are so arranged that when the arm 40 is in a vertical position the brush 43 lies between contact segments 46 and 47, and engages contact segment 50. The brush 44 also engages contact segment 50 and lies between contact segments 51 and 52, while the brush 45 engages contact segment 54 and lies between contact segments 52 and 53. The segments 46 and 47 are electrically connected and segments 51 and 53 are also electrically connected.
- 30 I shall now describe the circuit arrangement of the controller: Current is supplied from main lines 55 and 56. The main line 56 is connected by conductor 57 to the controlling arm 14. The contact segment 22 is connected by conductor 58 to contact segment 54 of the pilot switch. Contact segment 18 is connected by conductor 59 to one terminal of the shunt field winding *f* of the motor, the other terminal of said winding being connected by conductor 60 to the main line 55. Contact segment 53 of the pilot switch is connected by conductor 61 to contact 8. Contact segment 52 is connected by conductors 62 and 63 to one terminal of the motor armature *a*, the other terminal of the armature being connected by conductor 64 to contact 9. Contact 13 is connected to conductor 64. Contact 12 is connected by conductor 65, through a resistance 66, to conductor 63. Contact segment 50 is connected by conductor 67 to main line 55. Main line 56 is connected by conductor 68 to one terminal of the winding 26, while the other terminal of the winding 26 is connected by conductor 69 to the fulcrum of the arm 28 through a resistance 70 to the contact 35. Contact 35 is connected by conductor 71 to contact 48, which is connected by conductor 72 to contact 49. Contact segment 47 of the pilot switch is connected by conductor 73 to one terminal of the winding 3, while the other terminal of the winding 3 is connected by conductor 74 to the first of the series of contacts 21, which is connected through a resistance 75 by conductor 76 to main line 56.

I shall now describe the operation of the controller: Assuming that the arm 40 of the pilot switch is in the position shown in the drawing, the main switch will be open and the arm 14 in its lowermost position. If now the arm 40 be moved to the right so as to bring the brush 43 into contact with the segment 47, the brush 44 into contact with segment 52, and the brush 45 into contact with the contact segment 53, circuit will be closed through the operating winding 3 of the main line switch. This circuit may be traced from main line 56 by conductor 57, through the arm 14 to the first of the contacts 21 by conductor 74, through the winding 3 by conductor 73 to contact segment 47, across brush 43 to segment 50, and thence by conductor 67 to the main line 55. This will energize the winding 3 and cause the same to close the main switch 1, thereby raising the contacts 6 and 7 from the contacts 12 and 13. As soon as the main switch is closed circuit will be closed through the motor armature *a*. The armature circuit may be traced from main line 56, by conductor 57, through the arm 14, brush 17, to the second of the series of contacts 21, through all of the resistance 23 to contact segment 22, by conductor 58 to contact segment 54, across brush 45 to contact segment 53, by conductor 61 to contact 8, across main switch 1 to contact 9, thence by conductor 64 through the armature *a*, by conductors 63 and 62 to contact segment 52, across brush 44 to contact segment 50, and then by way of conductor 67 to the main line 55.

The shunt field winding *f* being connected across the supply circuit, the same will be energized before the armature circuit is closed. The circuit for the shunt field winding *f* extends from main line 56 by conductor 57, through the arm 14, brush 16 to contact segment 18, thence by conductor 59 through the shunt field winding *f*, and by conductor 60 to the main line 55. In this position of the pilot switch it will be seen that all of the armature resistance 23 is included in circuit with the armature *a*, and, therefore, the motor will be operated at a slow speed. The pilot switch may be left in this position as long as desired. The motor circuit may be opened at any time by merely moving the arm 40 back to a central position, which opens the circuit of the operating winding of the main switch. The main switch will then fall and open the motor circuit. When it is desired to increase the motor speed, the arm 40 of the pilot switch is moved to its extreme right-hand position, in which position the brush 43 will engage contact 49. Circuit will then be closed through the operating magnet 26 of the speed controller. This circuit extends from the main line 56 by conductor 68, through winding 26 by conductor 69, through the arm 28, lug 33, 130

switch 34, contact 35 by conductor 71 to contact 48, by conductor 72 to contact 49, by brush 43 to contact segment 50, and thence by conductor 67 to main line 55. The magnet 26 will then respond and raise its plunger 25, thus raising the arm 14.

As shown in the drawing, the stationary plug is adjusted to permit the plunger 25 to raise the arm 14 until the brush 17 engages the contact segment 22, and the brush 16 engages the first of the contacts 19. It will thus be seen that as the arm 14 is raised it will gradually remove all of the armature resistance from circuit, and then insert one step of the field resistance in circuit.

While I have shown the device set for merely inserting a portion of the field resistance, it should be understood that the device may be set so as to insert all of the field resistance, or to remove only a part of the armature resistance, as desired, according to the speed at which it is desired to operate the motor. It will thus be seen that in the final position of the pilot switch, the motor will be gradually brought up to the maximum speed and will continue to operate at a maximum speed until the main switch 1 is opened, or, until the brush 43 is moved off of the contact 49, whereupon, the winding 26 would be deenergized and the arm 14 would fall; first removing the field resistance from circuit and then inserting the armature resistance in circuit. The motor would then continue to operate at a slow speed until the arm 40 of the pilot switch was moved to the position shown in the drawing.

Upon the opening of the main switch 1, the contacts 6 and 7 carried thereby, will engage the contacts 12 and 13 and establish a dynamic braking circuit across the terminals of the armature α . This circuit may be traced from one terminal of the armature α by conductor 64 to contact 13, to contact 7, across the spring arms of the main switch to contact 6, to contact 12, thence by conductor 65 through the resistance 66 and by conductor 63 to the opposite terminal of the armature. The establishment of the braking circuit just described, will quickly bring the motor to a state of rest.

As soon as the arm 14 leaves the first of the series of contacts 21 upon its upward movement, the short-circuit around the resistance 75, through said arm, is opened and said resistance inserted in circuit with the winding 3. The circuit of the winding 3 will then extend from conductor 57 by conductor 76, through the resistance 75 to the first of the contacts 2, and thence through the winding 3, as already traced. The insertion of the resistance 75 cuts down the flow of current through the winding 3 to an amount just sufficient to maintain the main switch closed, and prevents the winding

from closing the main switch after the same has been opened. It will thus be seen that after the main switch 1 is opened, either by the failure of voltage, or by the operation of the pilot switch, said main switch cannot again be closed until the arm 14 reaches its lowermost position, whereupon it will short-circuit the resistance 75 and permit the winding 3 to respond. The motor is thus protected against damage in case an attempt is made to again start the same before the armature resistance is inserted in circuit.

If it is desired to operate the motor in the opposite direction from that previously described, the arm 40 of the pilot switch is moved to the left so as to move the brush 43 into engagement with the contact segment 46; the brush 44 in contact with the segment 51, and the brush 45 in contact with segment 52. In this position of the pilot switch, circuit will first be closed through the winding 3 and the main switch 1 will be closed thereby, thus closing the armature circuit. The armature circuit may now be traced from conductor 56, through the arm 14, through the resistance 23, contact segment 22, conductor 58 to segment 54, across brush 45 to segment 52, thence by conductors 62 and 63, through the motor armature α , by conductor 64 to contact 9, across switch 1 to contact 8, by conductor 61 to segment 53 of the pilot switch, across to segment 51, by brush 44 to segment 50, and thence by conductor 67 to main line 55. It will thus be seen that current flows through the motor armature in an opposite direction to that previously described, and, therefore, the motor will run in an opposite direction. The field circuit may be traced as already described. When it is desired to cause the motor to operate at its maximum speed, the arm 40 is moved to its extreme left-hand position, whereupon the brush 43 will engage contact 48 and close the circuit of the winding 26. The winding 26 will then respond and draw the arm 14 upwardly to gradually remove the armature resistance from circuit and then insert the field resistance.

Having thus described my invention, what I claim as new and desire to secure by Letters Patent, is:

1. In a controller for electric motors, in combination, an automatically operated main switch, a pilot switch adapted, when in a predetermined position, to cause said main switch to respond for obtaining a slow speed of the motor, and an automatically operated accelerating device arranged to respond when the pilot switch is moved to another position to increase the speed of the motor, said pilot switch having contacts included in the motor circuit for controlling the direction of flow of current therein.

2. In a controller for electric motors, in combination, an electroresponsive main

- switch, an electroresponsive accelerating device, and a pilot switch directly controlling the energizing circuits of said main switch and said accelerating device and movable 5 into a position for causing response of the main switch alone for slow speed and into another position for also causing the accelerating device to respond to increase the motor speed, said pilot switch inherently 10 controlling the direction of operation of the motor.
3. In a controlling device for electric motors, in combination, an automatically operated main switch, an automatically operated speed controlling device, means for adjusting said device to cause the motor to operate at different predetermined speeds, and a pilot switch adapted, when in one position, to cause said main switch to be 15 closed and when in another position to cause the operation of said speed controlling device.
4. In a controlling device for electric motors, in combination, a main switch, an electromagnetic winding for operating the same, a speed controlling device, an electromagnetic winding for operating the same, means for adjusting said controller to cause the motor to operate at different predetermined speeds, and a pilot switch adapted, when in one position, to close the circuit of the operating winding of said main switch and when in another position to close the circuit of the operating winding of said 25 30 35 speed controlling device.
5. In a controller for electric motors, in combination, a pilot switch having contacts for reversing the motor, an automatically operated main switch controlled directly by said pilot switch and adapted, when closed, to cause the motor to operate at a slow speed, an automatically operated accelerating device for the motor controlled by said pilot switch, said pilot switch being movable to cause the 40 45 50 operation of both the main switch and accelerating device or the main switch alone, and means whereby the maximum speed of the motor may be varied at will independently of said pilot switch.
6. In a controller for electric motors, in combination, a pilot switch movable in opposite directions for inherently varying the circuit connections of the motor to cause the same to operate in either direction, an electroresponsive main switch, and an electroresponsive accelerating device for the motor, said main switch and accelerating device being controlled directly by said pilot switch, and said pilot switch being adapted, when 55 60 65 moved in either direction, to cause both said main switch and said accelerating device to
- respond to bring the motor up to a predetermined high speed or to cause the main switch alone to respond for obtaining a slow speed of the motor. 65
7. In a controller for electric motors, in combination, an automatically operated main switch, an automatically operated speed controlling device, means for adjusting said device to cause the motor to operate at different predetermined speeds, and a pilot switch adapted to cause the motor to operate in either direction, said pilot switch, when in certain positions, being adapted to cause said main switch to be closed and when in other 70 75 positions to cause said speed controlling device to be actuated.
8. In a controlling device for electric motors, in combination, a main switch, an operating winding therefor, a speed controlling device, an operating winding therefor, means for adjusting said speed controlling device to cause the motor to operate at any predetermined speed, and a pilot switch for causing the motor to operate in either direction, said switch, when moved in either direction, being adapted to first close the circuit of the operating winding of said main switch and then to close the circuit of the operating winding of said speed controlling 80 85 90 95 device.
9. In a controller for electric motors, in combination, an automatically operated main switch, an adjustable automatically operated speed controlling device, a pilot switch adapted, when in one position, to cause said main switch to be closed and when in another position to cause said speed controlling device to be actuated, and a dynamic braking circuit across the terminals of the motor armature adapted to be completed when said main switch is open. 100
10. In a controller for electric motors, in combination, an automatically operated main switch, an adjustable automatically operated speed controlling device, a pilot switch movable in opposite directions to reverse the operation of the motor, said pilot switch, when moved in either direction, being adapted to first cause the operation of said 105 main switch and then cause the operation of said speed controlling device, and a dynamic braking circuit across the terminals of the motor armature adapted to be closed by said main switch when open. 110
- In witness whereof, I have hereunto subscribed my name in the presence of two witnesses. 115
